CHAIN LINK BLANK AND PROCESS FOR MAKING CHAIN LINKS

Henry St. Pierre, Worcester, Mass.

Application August 24, 1942, Serial No. 455,884

6 Claims.

(Cl. 59—35)

This invention relates to new and improved forged chain links and to methods of making the same.

Objects of the invention include the provision of a novel method of manufacture of locking links of the types disclosed in part in my Patent No. 2,277,567, dated March 24, 1942, and embodies the steps of forging blanks in the shape of an E with the two eye-forming arms extending from the center of the blank outwardly at angles, or inclined to each other, but in the plane of the link, said arms having generally opposed connecting portions at their ends, heating the center of the blank where the arms join, and then pressing the arms against a surface or die to swing or pivot them bodily inwardly toward each other to be connected, with the result that little if any deformation of the arms is necessary.

Further objects of the invention include the provision of a chain link center at the point of the initial forged connection of the eye arms at the solid side of the link, such center being forged thin or narrow in a plane normal to the link plane, and elongated at such center in said normal plane, to provide a substantially easy pivot or swing center for the arms, but at the same time providing sufficient metal at this center for a subsequent forging operation to complete the solid side of the link with the desired metal section.

Another object of the invention is to provide an open-side link blank having a pair of generally C-shaped eye-forming arms extending in opposed relation but at angles to each other, these arms being initially forged in one unitary piece with corresponding portions of the arms joined at a center, and if desired, a stud and connecting member may be formed at the same time at this center.

Other objects and advantages of the invention will appear hereinafter.

Reference is to be had to the following drawing in which

Fig. 1 is a view showing one form of finished locking link assembled in a chain;

Fig. 2 shows the original blank from which the finished link is to be made;

Fig. 3 is a partial view of the blank of Fig. 2, looking in the direction of arrow 3 in Fig. 2;

Fig. 4 is a view of the blank of Fig. 2 after the twisting of the stud bore element;

Fig. 5 is a section on line 5—5 of Fig. 3; and

Fig. 6 illustrates a blank for making the type of link shown in Fig. 1 but by a different method

of connecting the ends of the blank at the open side of the link.

The herein disclosed invention is not limited to the illustrated blanks and links but may be practiced with plain links having no studs and with links having different means of securing the link arms together. However, I have illustrated the invention as applied to certain embodiments for the purpose of providing a clear description and disclosure.

In Fig. 1 the finished locking link is shown as connecting a pair of solid links 10, and this locking link, in finished form, is similar in many respects to that shown in Fig. 1 of my above identified patent. This link comprises a solid side 12, a stud 14, a stud bore element 16, and a pair of opposite eye-forming arms 18 connected to the stud bore element by means of shoulders 20. It is this link which is to be made by my new method.

Fig. 2 shows the original forged blank which comprises a pair of generally opposed C-shaped arms 22 located at an angle to each other and connected at the center 24 of the solid side of the link blank to form a V therebetween in such a way as to provide an open side for the link blank while maintaining the C-shape of the arms. The exact angle at which the arms are connected is not important but it is less than 180° in all cases, and it will be clear from Fig. 2 that a very wide opening between the free ends of arms 22 is thereby afforded.

In the embodiment illustrated, a stud 26 projects inwardly from the center 24 and this stud is formed with a barrel or bore element 28 having cup-shaped recesses 30 located normal to the plane of the blank. These recesses are provided for the reception of shouldered connecting elements 32 at the free ends of arms 22. The barrel or stud bore element 28 is relatively short and thick and provides a large amount of metal for a purpose to be described.

An important aspect of the blank resides in the reduced thickness of the center portion 24 of the solid side of the link, and in its corresponding elongation in a direction parallel to the stud bore element 28 as shown in Figs. 2 and 3, or in other words the center 24 is reduced in a direction transverse of the blank and increased in a direction normal to the plane of the blank. The reason for this construction will be explained below but it is here pointed out that the total cross section of the center 24 is sufficient to finally provide a normal metal section at the link's solid side 12 in Fig. 1, and as originally forged, the

center 24 is seen to be provided with oppositely extending humps or projections 34 which will supply metal to fill out the reduced center.

It will be apparent to one skilled in the art that the above described blank is easily forged in a single set of dies by straight hammer blows operating normal to the plane of the blank, there being sufficient draw for the dies over the entire surface of the blank.

A pair of solid links such as those at 10 may be easily slipped over the free ends of arms 22 to be included in the eyes of the blank and then the stud bore element 28 is twisted 90°, as for instance indicated by the arrow in Fig. 3, so that it lies in the plane of the blank as shown in Fig. 4, and the solid links 10 may be thereby secured as the openings between the stud bore element and the free ends of arms 22 are now considerably reduced.

The thus assembled chain is now ready to have the open side of the locking link blank closed, and this is done by heating the center of the blank, grasping the stud bore element by any convenient means, and applying pressure thereto in the direction of arrow A in Fig. 4, with the outside surfaces, as 36, of the C-shaped arms abutting a plane surface or held in a die or the like. This action clearly will cause arms 22 to pivot or swing bodily inwardly toward each other as indicated by arrows B, to enter shouldered connecting portions 32 into recesses 30, this action being aided by the reduced section at center 24, which has been heated as stated. The arms 22 are cold, and will therefore swing inwards without any deformation so that the final arms 18 are in the form as forged originally at 22. As a practical matter, a blow or two may sometimes be found desirable to completely seat the portions 32 in the recesses.

The chain is now ready for the final step which is a forging operation. The locking link blank is heated at its center, including center 24 and its humps, and the stud bore element, the arms 22 still being cold if desired. The blank is then placed in an appropriate die and pressure by hammering is applied to the entire blank in a direction normal to the plane thereof. This hammering, in a single operation, shapes the center 24 to the desired final section, rounding it off, and at the same time forges the metal of the stud bore element to interlock with the shoulders at 32, and also may be utilized to spread the metal of the stud bore element to finish off this side of the locking link to leave no parts or separations. This method heat treats the stud bore element, stud, and center portion 24 as well as providing the final forging operation to produce an all forged, solid, and sturdy locking link, without heating or deforming the arms 22.

The modification of Fig. 6 illustrates a blank forged to carry out the above method with a locking link as disclosed in my co-pending application S. N. 449,931, filed July 6, 1942, Patent No. 2,363,271. In Fig. 6, the center portion 24, humps

34, and arms 22 are the same as in Fig. 2, but the method of connecting the ends 38 of the arms and stud 40 is by welding with subsequent forging in a die as described in said application. Otherwise the method and blank are the same as before and it will be seen that other methods of connection may be used without departing from the scope of the present invention.

Having thus described my invention and the advantages thereof, I do not wish to be limited to the details herein disclosed, otherwise than as set forth in the claims, but what I claim is:

1. A locking chain link blank having a solid side and an open side, said solid side comprising a pair of mutually inclined arms joined together at adjacent ends to form a center portion, said center portion being reduced in thickness relative to the free ends of said arms.

2. A locking chain link blank as recited in claim 1 wherein said center portion is elongated in a direction at right angles to the plane of the blank.

3. A locking chain link blank as recited in claim 1 wherein said center portion is provided with a hump extending in a direction normal to the plane of the blank.

4. A locking chain link blank comprising a pair of generally C-shaped elements joined together at adjacent ends of the elements, the latter being relatively inclined to form an E-shaped locking link having a solid side in the general form of a V, the apex of the V corresponding to the center of the link, said solid side being reduced in thickness in a direction in the plane of the link and increased in thickness in a direction in a plane normal to the plane of the link, the section of the apex and of the elements being substantially equal in area.

5. The method of making a link including the steps of forming a blank having curved ends and a center stud, said ends being located to extend from a reduced humped end of the stud at angles to each other so that a side of the blank is open, pivoting the ends without deformation about said reduced end, toward each other to the other end of the stud, securing the ends to the stud at said other end, and forging the hump to add material to the link at the reduced portion.

6. The method of making a link from a blank comprising a pair of C-shaped elements joined together at corresponding ends thereof, said elements being at an angle to each other to provide an open side for the blank, there being a reduced area in one direction at the junction of the arms and an enlarged area in a direction normal thereto, said method comprising the steps of heating at least the junction, pivoting the C-shaped arms together about the junction as a center, providing a connection for the ends of the arms, heating said connection and said junction, and forging both of the latter areas at once to finish the reduced and enlarged areas to normal and to secure the arm ends together.

HENRY ST. PIERRE.
